TIMING MECHANISM FOR MEASURING THE DURATION OF THE DRAW OF A FIREARM

Willard Alden Thomas, Cincinnati, Ohio, assignor to Kilgore, Inc., Westerville, Ohio, a corporation of Ohio

Filed Mar. 27, 1959, Ser. No. 802,357

6 Claims. (Cl. 42—1)

This invention relates generally to firearms and more particularly to a firearm provided with a device for indicating the elapsed time interval between drawing the firearm and actuating the trigger.

An object of the present invention is to provide a novel combination of a pistol and timing device for the purpose of timing the duration of a "draw," i.e., the time interval from the time the firearm is grasped until it is fired.

Another object of the present invention is to provide a combination timing device and firearm wherein the firearm is in the form of a toy pistol and in which a contest or game may evolve from utilizing the novel structure.

Other objects and the nature and advantages of the invention will become apparent from the following description taken in conjunction with the accompanying drawings, which show one embodiment of the invention, in which:

Fig. 1 is a side elevational view of the principal parts of the invention, with portions being broken away for clarity, and with the outline of the firearm handle being shown by phantom lines;

Fig. 2 is a fragmentary side elevational view of the novel firearm showing the indicia means for indicating the time lapse during the draw;

Fig. 3 is a view similar to Fig. 1, showing the position of the parts after the handle of the firearm has been grasped, the timing means has been activated and the trigger is being pulled;

Fig. 4 is a view similar to Figs. 1 and 3, illustrating the position of the parts upon firing and deactivation of the timing means;

Fig. 5 is a section taken substantially on line 5—5 of Fig. 4;

Fig. 6 is an enlarged fragmentary diagrammatic view of the timing gear relative to the cooperating escapement portion of the timing means;

Fig. 7 is an enlarged fragmentary section taken on line 7—7 of Fig. 4; and

Fig. 8 is an enlarged side elevational view of a support plate of the invention.

The firearm in accordance with the present invention includes a timing means, actuating means for setting the timing means into operation when the handle of the firearm is grasped when removing it from the holster prior to firing; deactivating means for stopping the timing means operated in response to the firearm being fired; and indicia means on the firearm indicating the elapsed time between the actuation and the deactivation of the timing means. Although the drawings illustrate a toy pistol, it should be understood that this invention can be applied to any firearm for training purposes and the like.

Referring to the drawings in detail, a fragmentary handle portion of a toy pistol adapted for the firing of percussion caps is indicated generally at 10. A hammer 12 adapted to strike the cap is pivotally mounted on a transverse shaft 14 to be pivoted thereabout during firing of the toy pistol. The hammer includes a laterally extending

2

stub shaft 16 upon which is journalled the upper end of a depening link element 18 which terminates in an off-set portion 20. The link element 18 is limited in its clockwise movement on the hammer by a laterally projecting stop pin 22 and is biased toward this stop pin 22 by a suitable link spring 24 extending around notched out portion 26 of the hammer and the upper surfaces of the link element 18.

Mounted on a transverse support shaft 30 is trigger 32 including a projecting step or point 34 engageable with the lower portion of the hammer 12 when the trigger is moved rearwardly during firing.

Mounted on a transverse support shaft 36 is an actuating lever 38 which is arcuate and substantially conforms with the shape of the undersurface of the handle of the gun. The handle is cut out at 40 to permit pivoted movement of the lever and a hair pin spring 42 is circumsposed about the shaft 36, one end 44 of the spring engaging the lever 38 to urge it outwardly, the other end 46 of the spring engaging beneath a transverse pin 48. The lever 38 has fixed thereto near its free end a rearwardly projecting abutment portion 50 which includes an upwardly disposed step 52 and a depending projection 53 the function of which will be described hereafter.

25 Mounted on the shaft 48 is a depending brake link 54, an intermediate portion of which abuttingly engages a pin 55, whereby a lower angulated end 56 thereof is urged toward a position to control the operation of a timing assembly indicated generally at 58. The brake link has 30 secured to its underside a laterally projecting element 60, slotted at 62 and capable of receiving the lower stepped portion 20 of the link 18 therethrough.

Referring to Fig. 1, it will be noted that during the normal position of the parts, the lever 38 is urged away from 35 the handle by spring 42, and the projection 53 on the abutment portion 50 engages a stop 64 on the handle. The step portion 20 of the link 18 is disposed in the slot 62 and the brake link 54 is biased downwardly or toward the timing assembly 58 with its lower portion 56 engaging one of 40 the teeth of the indicator wheel to prevent rotation of the same.

The timing assembly in this exemplary embodiment is disclosed as one utilizing a conventional escapement mechanism and coil spring, however, it is considered to be 45 within the purview of the invention to use other timing assemblies. The timing assembly 58 comprises a main support shaft 66 extending between a mounting plate 68 and a plate 70 spaced therefrom. The shaft 66 is knurled throughout its length and has secured thereto one end of a 50 convoluted spring 72 which is anchored at its other end in a surrounding housing 74 projecting laterally from the mounting plate 68. Fixed to the shaft 66 for rotation is an indicator wheel 76 which includes peripheral indicia visible through an opening 78 in the left side of the handle 55. The opening 78 includes a magnifying glass 80 to aid in reading the indicia on the wheel 76. Thus when the indicator wheel is rotated in a clockwise direction, the spring is wound.

Also mounted on the shaft 66 is a timing gear 82 which 60 rotates with the shaft 66 under the power of the coil spring 72. Mounted in spaced relation from and parallel to the shaft 66 is an escapement support shaft 84 upon which is fixed an elongated oscillator or element 86. The oscillator element 86 includes spaced lower ends 88 and 90, shown diagrammatically in Fig. 6, which alternately engage the teeth 92 of the timing gear due to oscillation of the oscillator element 86. This, as is conventional in such escapement mechanisms, permits a step-by-step rotation of the wheel 76. The lower or butt end of the handle 65 is open at 94 to permit manual engagement of the periphery of the wheel 76 and the rewinding of the spring 72. The wheel 76 will turn counter-clockwise during a timing 70

operation and includes a laterally projecting stop pin 85 engageable with an abutment portion on the plate 70 which serves to orient the indicia at a "0" reading before the opening 78. The wheel 76 is toothed and calibrated in 50 increments equivalent to two-hundredths of a second each, and the dial will make one revolution in one second. The handle, as will be seen in Fig. 2, has an indicator portion 94 readily alignable with the indicia calibrations 96 on the indicator wheel 76 running from zero to ten, with four witness marks between each digit.

Operation of the device is as follows: First of all, the indicator wheel 76 is wound in a clockwise direction back to the zero setting by thumb action on the lower portion of the indicator wheel extending through the handle portion at the base of the gun butt. The toy gun is then housed in a holster. At this point, the parts are disposed in the positions shown in Fig. 1 with the actuating lever 38 spaced from the handle 10, and the lower portion 56 of the brake link 54 in engagement with the teeth of the indicator wheel 76, thus preventing rotation thereof. When the signal is given, the toy gun is drawn from the holster, aimed and fired. Upon drawing the toy gun from the holster the handle is grasped thereby depressing the lever 38 against the handle 10 to the position shown in Fig. 3. When this occurs, the brake link 54 is moved away from the indicator wheel 76 allowing the wheel to rotate in a counter-clockwise direction. The movement of the brake link 54 is actuated by action of the movement of the portion 50 of the lever 38 against the brake link portion 60. The speed of rotation of the indicator wheel is controlled by the escapement mechanism including the counter balanced oscillator timing gear 82 and the convoluted spring 72. A step-by-step rotational movement is permitted in the usual manner of escapements by action of the oscillator 86 on the timing gear 82. The number of teeth on the timing gear determines the time increments of escapement.

When the trigger 32 is pulled, the counter-clockwise revolution of the indicator wheel 76 is stopped as follows. The pulling back of the trigger 32 causes the trigger point 34 to rotate in a counter-clockwise direction about the trigger pivot 30. This in turn rotates the hammer 12 in a clockwise direction about the hammer pivot 14, as shown in Fig. 3, the link 18, which is attached and pivoted to the hammer 12, moves down through the brake link slot 62 and is then forced by the link spring 24 to move toward the lever 38 engaging the brake link element 60. The hammer 12 revolves in a clockwise direction until the continued revolution of the trigger point 34 causes the hammer point to fall from the trigger point, as shown in Fig. 4. The hammer spring then forces the hammer to return to its original position. This causes the link 18 to move up lifting the brake link element 60 from the step 52 on the lever 38 and permits engagement of the brake link end 56 with the indicator wheel 76 stopping the rotation.

As the hammer continues its motion to the rest position the stop pin 22 forces the link 18 away from engagement with the brake link allowing the brake link element 60 to fall on the upper step 52 of the lever 38 as best shown in Fig. 1.

The time of the action can now be read from the indicator wheel through the opening 78 in the side of the handle.

Upon release of the lever 38, the lever spring 42 forces it away from the mechanism allowing the brake link element 60 to drop to the step. Upon release of the trigger 32, the trigger spring, not shown, returns the trigger point to its original position. The indicator wheel 76 can now be rewound and the full cycle repeated.

It is apparent that a pair of these toy pistols can be utilized by two contestants to determine which contestant has the faster draw.

Although the novel combination has been described in connection with toy pistols, it is apparent that such a mechanism can be embodied in any type of firearm to

give readings in the time of draw. This is useful in training police officers, soldiers and others who must be proficient in a rapid draw.

It is contemplated that other types of timers can be substituted for the escapement mechanism illustrated, such as pneumatic timers or inertia timers. It is only necessary that the timer be included within the firearm structure, that it is actuated by the drawing of the gun, that it be deactivated by firing the trigger, and that means be provided for indicating the elapsed time.

The initiation or activation of the timer can be accomplished by other means than is shown in the drawings. It is contemplated that in place of the lever 38, other structure can be utilized. For example, a button on the side of the gun could be provided, which is forced into a closed position as the gun is placed in the holster. Thus, the instant the gun is drawn from the holster, the button snaps outwardly and the timer is actuated. A dog mechanism can be provided with such a button arrangement, so that the depressing of the button resets the dog mechanism allowing the timer to start when the button is released.

Another method of actuating the timer mechanism contemplated by this invention is the use of a button on the side of the gun which can be held depressed by the user, and when a signal is given the user releases the button to permit the timer to start. Other mechanisms to activate the timer mechanism are within the broad scope of this invention.

It will be obvious to those skilled in the art that various changes may be made without departing from the spirit of the invention and therefore the invention is not limited to what is shown in the drawings and described in the specification, but only as indicated in the appended claims.

What is claimed is:

1. In a pistol including a trigger operated hammer and a handle, a timing assembly in said handle and including an indicia portion for indicating increments of elapsed time, an actuating lever pivotally mounted on said handle and compressible when said pistol is grasped, brake means operatively connecting said actuating lever to said timing assembly whereby said timing assembly is activated in response to depression of said lever, and linkage means operatively connected to said brake means and said hammer for stopping operation of said timing assembly in response to firing movement of said hammer whereby said indicia portion indicates the elapsed time between grasping the handle and the firing of the pistol.

2. The structure of claim 1 in which said timing assembly includes an indicia reset portion accessible from the exterior of said pistol handle for resetting the indicia portion to a zero position after each operation, a spring operatively connected to said indicia portion, said spring being rewound in response to resetting of said indicia portion to the zero position.

3. The structure of claim 2 in which said timing assembly includes a timing gear, said spring being operatively connected to said timing gear, and an escapement control operatively connected to said timing gear to permit step-by-step movement of said timing gear and said indicia portion during the period between drawing and firing of said pistol.

4. In a pistol including a trigger operated firing means and a handle, timing means mounted on said pistol and including an indicia portion for indicating increments of elapsed time, an actuating lever mounted on said handle and compressible when said pistol is grasped, said actuating lever being operatively connected to said timing means for actuating operation of said timing means when said lever is depressed, means operatively connecting said firing means and said timing means for stopping operation of said timing means in response to firing movement of said firing means, whereby said indicia portion

indicates the elapsed time between grasping the handle and the firing of the pistol.

5. The structure of claim 4 in which said timing means includes an indicia reset portion accessible from the exterior of said pistol for resetting the indicia portion to a zero position after each operation, a spring operatively connected to said indicia portion, said spring being rewound in response to resetting of said indicia portion to the zero position.

6. The structure of claim 5 in which said timing means includes a timing gear, said spring being operatively connected to said timing gear, and an escapement control

operatively connected to said timing gear to permit step-by-step movement of said timing gear and said indicia portion during the period between drawing and firing of said pistol.
